COMBINED CLAMP, TELEPHONE HOOK AND PAD HOLDER

Anthony Victor Farina, New Kensington, Pa.

Application December 23, 1958, Serial No. 53,874

Term of patent 7 years

(Cl. D26—14)

Fig.1.

Fig.2.

Fig.3.

Fig. 1 is a top view of a combined clamp, telephone hook and pad holder showing my new design;

Fig. 2 is a front elevational view, the rear being substantially a mirror image thereof; and

Fig. 3 is a front perspective view thereof.

The broken line showing of a telephone and pad in Fig. 3 is for illustrative purposes only.

I claim:

The ornamental design for a combined clamp, telephone hook and pad holder, substantially as shown and described.
